UNITED STATES PATENT OFFICE.

ALBEN E. LUNDELL, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 28, 1920. Serial No. 377,358.

To all whom it may concern:

Be it known that I, ALBEN E. LUNDELL, a citizen of the United States, residing at Chicago, in the county of Cook, State of Illinois, have invented certain new and useful Improvements in Telephone-Exchange Systems, of which the following is a full, clear, concise, and exact description.

This invention relates to telephone exchange systems and more particularly to circuits and apparatus for extending connections from an automatic exchange to manual exchanges of the magneto type.

In small rural communities, exchanges of the magneto type are quite frequently employed. Lines of such exchanges are equipped with magneto generators at the substations and with drop signals at the central exchange by means of which the subscribers may signal the operator to initiate a call. The operators' cord circuits of such exchanges are also provided with supervisory drop signals which may be operated by a subscriber after a cord circuit has been connected with his line for the purpose of giving the operator a disconnect signal. When it is desired to establish a connection between a subscriber in an automatic exchange and a subscriber in such a magneto exchange over a trunk line extending between the exchanges, some provision is necessary for supplying magneto current to the trunk line for the purpose of operating the drop signals at the magneto exchange, since the automatic exchange is of the common battery type and therefore the current supplied to lines or trunks to which the selector switches of such exchange have access is not of such character as will operate the drop signals.

The principal object of this invention is to overcome this difficulty by providing means associated with the interoffice trunk extending between an automatic exchange and a magneto exchange, for operating the signaling devices at the magneto exchange both upon seizure and release of the trunk circuits.

A feature of the invention resides in the provision of means associated with an interoffice trunk extending between an automatic and a magneto exchange comprising

a group of relays and a source of alternating current for causing the application of the alternating current to the incoming end 55 of the trunk circuit as soon as the outgoing end of the trunk circuit is seized, and again upon release of the outgoing end of the trunk circuit, for operating drop signals associated with the incoming end of the trunk 60 circuit and with the cord circuit at the magneto exchange.

A further feature of the invention resides in the provision of a double wound quick acting relay and a slow acting relay with 65 their windings and contacts so interrelated that the quick acting relay retains its armatures attracted for an appreciable time even upon a momentary initial impulse through one of its windings, for the purpose of 70 maintaining the connection of the source of alternating current to the incoming end of the interoffice trunk for a period sufficient to insure the operation of the drop signals 75 at the magneto exchange.

Other features of the invention will be apparent as the description of the improved system progresses. The invention will now be described in connection with one specific embodiment of the genus of the invention. 80

In the accompanying drawings,—

Fig. 1 illustrates a calling subscriber's line, an operator's connecting circuit, and a group switch which has access to trunk circuits extending to other selector switches 85 in the automatic exchange, and to interoffice trunk circuits extending to an outlying magneto exchange;

Fig. 2 shows a final selector switch having access to subscribers' lines in the automatic exchange, and one subscriber's line to which such selector has access;

Fig. 3 shows an operator's controlling apparatus by means of which the selector switches may be set; and

Fig. 4 shows an interoffice trunk circuit terminating in a jack before an operator's position in a magneto exchange, a cord circuit in such an exchange, and a subscriber's line, together with such circuits and equipment associated with the trunk circuit as is necessary to operate the drop signals at the magneto exchange.

Fig. 2, when placed to the right of Fig. 1,

Fig. 3 when placed beneath Fig. 1 and Fig. 4 when placed to the right of Fig. 3 shows such portions of an organization of circuits and apparatus as is necessary to complete a 5 connection either between subscribers' lines terminating in the same automatic exchange or between a subscriber's line of the automatic exchange and a subscriber's line of the magneto exchange.

10 The selector and sequence switches and controlling apparatus therefor will not be disclosed in full in the following description of this system, switches of this type being well known in the art. A complete 15 description of the operation of such switches may be found in Patent No. 1,168,319, issued January 18, 1916 to A. E. Lundell.

It is thought a clearer understanding of 20 the invention will be had from a detailed description of the establishment of connections between subscribers. It will first be assumed that the calling subscriber at station 100 desires to obtain a connection with the subscriber at station 200 in his own exchange.

25 *Extension of connection between subscribers in the automatic exchange.*

Assuming that the calling subscriber at 30 station 100, desires to obtain a connection with a subscriber at station 200, he will remove his receiver from the switchhook, and close thus a circuit for the line relay LR which lights a calling signal CL. The operator noticing that the lamp CL is lighted, 35 inserts a plug 101 of an idle link circuit at her position into a jack 102 in which the calling line terminates, whereupon a circuit is closed from grounded battery through the winding of cut-off relay CO, sleeve contacts of jack 102 and plug 101, and the winding of 40 relay 103 to ground. Relay 103 closes a circuit from grounded battery, through the power magnet of sequence switch 105, through the sequence switch contact 104, 45 thence to ground at the armature and front contact of relay 103. Under the control of a master spring 106, sequence switch 105 moves out of position 1 and into position 2. A circuit is now closed from ground, through sequence switch contact 107, conductor 108 50 and contact 300 of sequence switch 301 and the winding of relay 302 to grounded battery. Relay 302 becomes energized and closes a circuit from ground, through its left-hand armature and front contact, the 55 contact 303 and the power magnet of sequence switch 301 to grounded battery. Under the control of the master spring 304, sequence switch 301 is moved out of position 60 1 and into position 3. Relay 302 does not become deenergized when sequence switch 301 leaves position 1, a circuit being closed from grounded battery, through the winding of this relay, sequence switch contact 65 305, the right-hand armature and front con-

tact of relay 302, conductor 306 and contact 109 of sequence switch 105 to ground.

The operator, by depressing her listening key 110 connects her telephone set 111 into telephonic association with the calling subscriber's line and in accordance with instructions received from the subscriber, she adjusts her controlling apparatus. Only two rows of keys are shown in Fig. 3, as it is thought sufficient for the purpose of the present invention to describe the setting of an interconnecting means such as a selector switch 112 and a connecting means such as a selectively operable connector switch 201, each in accordance with one digit of the 70 called subscriber's number. It will be obvious to those skilled in the art that both switches will be set in accordance with a plurality of digits in order to extend the calling line toward the called line, and for this purpose a plurality of rows of keys must be provided at the operator's position. Supposing, however, that the called subscriber's line may be seized by causing selector switch 112 to take three steps and connector switch 201 to take ten steps, the operator will depress keys 310 and 311 and a start key 312. A circuit is established from ground, through the contact of key 312, the contact 313 and the power magnet of sequence switch 301 to 75 grounded battery for moving this sequence switch into position 4. A circuit is then closed from grounded battery, through the winding of relay 113, sequence switch contact 114, conductor 115, sequence switch contact 314, the outer armature and back contact of the upper counting relay O, the winding of a stepping relay 315, conductor 316, and thence to ground at sequence switch contact 116. Relays 113 and 315 become energized in this circuit, relay 113 closing a circuit from ground, through its right-hand armature and front contact, sequence switch contact 117, conductor 118, the power magnet of sequence switch 105 to grounded battery for moving this sequence switch into 80 position 3. Relay 113 remains energized upon the opening of contact 114 due to the closure of a substitute path through the left-hand armature and front contact of this 85 relay and sequence switch contact 119.

Upon the energization of stepping relay 315, a circuit is closed from ground, through the front contact and armature of this relay, sequence switch contact 317, conductor 318, the contact of key 310, conductor 322, the armature and back contact of the upper counting relay 2 and the winding of the lower counting relay 2 to grounded battery. The lower counting relay 2 energizes and 90 closes a circuit from ground, through sequence switch contact 320, conductor 321, the armature and front contact of the lower counting relay 2 and the windings of the upper and lower counting relays 2 to 95 130

grounded battery. The upper counting relay 2, however, cannot become energized due to the presence of the short circuit around its winding, to ground through the 5 armature and front contact of stepping relay 315.

In position 3 of sequence switch 105, a circuit is closed from grounded battery, through the winding of the up-drive magnet 120 of the group selector switch, through sequence switch contact 121 and thence to ground, through the front contact and right-hand armature of relay 113. Magnet 120 attracts its armature 122 and presses the 10 depending portion 123 of the switch shaft against the constantly rotating up-drive roller 174. The switch shaft with the brushes 124, 125 and 126 and commutator 15 wipers 127 and 128 is thereby moved in an upward direction, the brushes 124, 125 and 126 wiping over the terminal bank 129 and the commutator wipers 127 and 128 over conducting and insulated segments of a 20 commutator plate 130. When the commutator wiper 128 engages a conducting segment 131, it connects ground through this segment and conductor 132, sequence switch contacts 133 and 119, through the winding of relay 113 to grounded battery, thus 25 shunting out the stepping relay 315. Relay 315 opens at its front contact and armature, the short-circuit of the upper counting relay 2, whereupon this counting relay becomes energized and connects conductor 322 30 through its armature and front contact, and armature and back contact of the upper counting relay 1, the winding of the lower counting relay 1 and conductor 323 to grounded battery. The lower counting 35 relay 1, however, cannot become energized until commutator wiper 128 is moved into engagement with an insulating segment 134 of the commutator plate, thereby permitting the reenergization of relay 315 which 40 again connects ground to the conductor 322.

The operation of the counting relays continues in substantially the same manner until the shaft of selector 112 has been moved upwardly three steps and the upper 45 counting relay O has become energized. This counting relay, upon energizing, opens at its outer armature and back contact, the fundamental circuit including relays 113 and 315 and closes, at its inner armature and 50 front contact, a circuit extending from ground at sequence switch contact 324, through the magnet winding of sequence switch 301 for driving the sequence switch out of position 4 and into position 6. When 55 the sequence switch leaves position 4, all the counting relays which have been locked up over conductor 321 become deenergized. Relay 113, upon deenergizing, closes a circuit from ground, through its right-hand 60 armature and back contact, sequence switch

contact 135, conductor 118, and the power magnet of sequence switch 105 to grounded battery for moving this sequence switch out of position 3 and into position 6. When sequence switch 105 leaves position 3, the 70 up-drive magnet 120 becomes deenergized.

A circuit is now closed from ground, through sequence switch contacts 136 and 137 and the right-hand winding of test relay 138 to grounded battery. Assuming that 75 the trunk line 202, 203, and 204, terminating in the first contact set of the third group of contacts of terminal bank 129 is the first to be engaged and is idle, that is to say, no busy ground potential is connected 80 to test contact 139 and the multiples thereof, then when the brushes of the selector engage this set of bank terminals, the selector switch need not be moved farther. When the trunk is idle, sequence switch 205, associated with selector 201, is in position 1, thus the trunk holding relay 206 is deenergized. 85

When the relay 138 is energized, a circuit was closed from the ground, through its right-hand armature and front contact, sequence switch contact 140, conductor 118 and through the power magnet of sequence switch 105 to grounded battery, for driving the sequence switch out of position 6 90 and into position 7. Upon leaving position 6, the sequence switch opens the initial energizing circuit of relay 138 at contact 136 and if the trunk terminals which the brushes 95 of the selector then engage are busy, the relay 138 will be maintained energized in positions 6 and 7 of the sequence switch for causing the movement of selector 112 to the terminals of another trunk. As soon 100 as the brushes engage the brushes of an idle trunk, this maintaining circuit for relay 138 is opened and as soon thereafter as the commutator wiper 127 engages an insulated segment 141 of the commutator 130, relay 138 becomes deenergized and opens the circuit which extended through sequence switch contact 145 and the magnet winding of the up-drive magnet 120, at its right-hand armature and front contact, thereupon causing 105 the brushes to be brought to rest on the terminals of an idle trunk. Relay 138 at its right-hand armature and back contact closes a circuit from ground, through sequence switch contact 146, conductor 118, and the power magnet of sequence switch 105 for 110 driving this sequence switch out of position 7 and into position 11. 115

Sequence switch 301 is now in position 6, sequence switch 105 in position 11, and sequence switch 205 in position 1 and all of 120 the counting relays employed in the operation of the group selector are now deenergized.

The fundamental circuit therefor will be 125 again closed but now from grounded battery, 130

through the winding of relay 207, sequence switch contact 208, trunk conductor 202, brush 124 of selector 112, sequence switch contact 150, conductor 115, sequence switch contact 314, the outer armature and back contact of the upper counting relay O, the winding of stepping relay 315, conductor 316, sequence switch contact 151, wiper 125 of selector 112, trunk conductor 203, and sequence switch contact 209 to ground. Relay 207 energizes in this circuit and closes, at its right-hand armature and front contact, a circuit extending through sequence switch contact 210, and through the magnet winding of sequence switch 205 to grounded battery for driving this sequence switch out of position 1 and into position 2. Upon leaving position 1, sequence switch 205 opens the initial energizing circuit of relay 207, but this relay is maintained energized over a locking circuit extending through its winding, its left-hand armature and front contact, through sequence switch contact 211, and thence over the circuit previously traced.

In position 2 of sequence switch 205, a circuit is closed from ground, through sequence switch contact 212, and the winding of relay 206 to grounded battery. This relay locks itself up from grounded battery, through its winding, its left-hand armature and front contact, test conductor 204 of the selected trunk circuit, selector brush 126, conductor 152, the inner left-hand armature and back contact of relay 138, and thence to ground. Relay 206 and at its right-hand armature and front contact closes a circuit extending through sequence switch contact 213 and through the magnet winding of sequence switch 205 to grounded battery, for driving this sequence switch out of position 2 and into position 3. In position 3 of sequence switch 205 a circuit is established for the up-drive magnet 215 of the final selector switch 201, which circuit extends from grounded battery, through the magnet winding 215, sequence contact 216 and thence to ground at the right-hand armature and front contact of relay 207. Magnet 215, by attracting its armature 217, presses the depending portion of the brush shaft 218 against the constantly rotating up-drive roller 219, whereby the switch shaft and the brushes 220, 221, and 222 and commutator wiper 223 are caused to move in an upward direction. The brushes 220 and 221, in which the trunk conductors 202 and 203 terminate, and the test brush 222 are adapted to wipe over a contact bank 224, in which called lines terminate and the commutator wiper 223 over conducting and insulated segments 225 and 226 of a commutator plate 227.

Stepping relay 315 was energized over the fundamental circuit in series with relay 207,

and upon energization closed a circuit from ground, through its front contact and armature sequence switch contact 330, conductor 331 and the contact of key 311, conductor 332, armature and back contact of upper counting relay 9, and the winding of the lower counting relay 9 to grounded battery. The counting relays operate in the same manner as above described, under the control of stepping relay 315.

The upward movement of the switch shaft of the final selector causes the commutator wiper 223 to traverse over the conducting and insulated segments 225 and 226 of the commutator plate 227, thereby intermittently connecting a shunt circuit around the winding of the stepping relay 315, which shunt circuit may be traced from ground at the commutator wiper 223, through the conducting segments 225 conductor 230, to sequence switch contact 231. After the switch shaft has been moved upwardly ten steps, the upper counting relay O will, in the well-known manner, become energized, opening at its outer left-hand armature and back contact, the fundamental circuit extending through the windings of relays 315 and 207, whereupon these relays become de-energized. The upper counting relay O also closes a circuit from ground, through sequence switch contact 324, the inner armature and front contact of the upper counting relay O, and power magnet of sequence switch 301, to grounded battery for driving the sequence switch out of position 6 and into position 16, whereupon a circuit is closed from ground, through sequence switch contact 335, conductor 336, contact 155 of sequence switch 105 and power magnet of sequence switch 105 to grounded battery, and this sequence switch is moved out of position 11 and into position 16. Upon the opening of contact 109 of sequence switch 105 when the sequence switch moves out of position 11, relay 302 becomes de-energized and closes a circuit from ground, through its left-hand armature and back contact, sequence switch contact 337 and the power magnet of sequence switch 301 to grounded battery for moving this sequence switch out of position 16 and into position 1.

Upon the deenergization of relay 207, when the upper O counting relay opened the fundamental circuit, the circuit of the up-drive magnet 215 is opened at the right-hand armature and front contact of relay 207 and a circuit is closed from ground, through the right-hand armature and back contact of relay 207, sequence switch contact 232, and the power magnet of sequence switch 205 to grounded battery for driving this sequence switch out of position 3 and into position 13. The brushes of the final selector are now brought to rest on the terminals of the desired line. After the

testing of this line in the well-known manner through the sequence switch contact 233, a ringing circuit is closed from a ringing current source 234, through the winding of relay 235, sequence switch contact 236, brush 221, the line loop of the desired subscriber's line, brush 220 and sequence switch contact 237 to ground. Upon the removal of the receiver at the called substation, marginal relay 235 becomes energized and closes a circuit from ground, through sequence switch contact 238, the front contact and armature of relay 235, and the power magnet of sequence switch 205 to grounded battery for driving this sequence switch out of position 13 and into the talking position 16. When sequence switch 205 leaves position 13, relay 235 becomes deenergized. The calling and called subscribers are now connected in a telephonic circuit indicated in heavy lines in the drawings.

Upon the establishment of the talking circuit to the line of the desired subscriber, the calling supervisory relay 246 becomes energized in a circuit extending from grounded battery, through the lower right-hand winding of repeating coil 247, the winding of supervisory relay 246, brush 221, over the subscriber's line loop back through brush 220, sequence switch contact 253, and to ground through the upper right-hand winding of repeating coil 247. Relay 246 energizes in this circuit and at its armature and front contact closes a circuit for the reversing relay 248, which circuit may be traced from grounded battery, through the winding of this relay, and thence to ground at the armature contacts of relay 246. Relay 248 by attracting its armatures reverses the connections between the terminals of the battery 249 and the conductors 202 and 203 of the trunk circuit, thereby causing the operation of the polarized supervisory relay 161 at the operator's position in such a manner as to indicate to the operator that the desired subscriber has responded.

The subscribers, desiring disconnection, restore their receivers to their respective switchhooks. The restoration of the calling subscriber's receiver causes the deenergization of the answering supervisory relay 160 at the operator's position to light the supervisory lamp in the well-known manner. The restoration of the receiver at the called subscriber's substation, causes the deenergization of supervisory relay 246 and the consequent deenergization of relay 248 which thereupon reverses the connection of the terminals of battery 249 to the trunk conductors 202 and 203 for causing the reverse operation of the polarized supervisory relay 161 to thereby light the calling supervisory lamp at the operator's position. The operator noticing these signals, removes the plug 101 from the jack 102,

whereupon relays CO and 103 become deenergized, the former restoring the connection of the windings of the line relay LR to the limbs of the calling subscriber's line, and the relay 103 closing a circuit from ground, through its armature and back contact and the contact 162 of the sequence switch, and thence to the power magnet of sequence switch 105 to grounded battery for driving the sequence switch out of position 16 and into position 18.

In position 18, a circuit is closed from grounded battery, through the winding of the down-drive magnet 163, which circuit may be traced from the winding of this magnet, through sequence switch contact 164, to ground. Magnet 163 presses the depending portion of the switch shaft 123 against the constantly rotating down-drive roller 166, whereby the switch shaft is moved downwardly into its normal position. When the shaft reaches its normal position, a circuit is closed from ground, through commutator wiper 127, normal segment 167, conductor 168 sequence switch contact 169, conductor 118, and thence to grounded battery through the power magnet of sequence switch 105 for driving this sequence switch out of position 18 and into position 1. When the sequence switch leaves position 18, the downdrive magnet 163 becomes deenergized.

As soon as the brush 126 of the group selector leaves the terminal of the trunk conductor 204, the locking circuit of relay 206 is opened and this relay becomes deenergized. At its left-hand armature and back contact, the relay connects the test conductor 204 to ground at sequence switch contact 240 to prevent the seizure of the trunk circuit by other group selectors until the final selector is completely restored to normal and, at its right-hand armature and back contact, closes a circuit extending through sequence switch contact 241 for driving the sequence switch 205 out of position 16 and into position 18.

In position 18, a circuit is closed extending from ground at sequence switch contact 242, through the winding of the down-drive magnet 243 for causing the restoration of the switch shaft of the final selector. The energization of magnet 243 presses the depending portion 218 of the switch shaft against the constantly rotating down-drive roller 254 which moves the switch shaft downwardly into normal position. Upon reaching its normal position, the commutator wiper 223 closes a circuit extending from ground, through this wiper, the normal segment 224 of the commutator, conductor 245, sequence switch contact 246, and through the magnet winding of sequence switch 205 for driving the sequence switch out of position 18 and into position 1. In

position 1 of sequence switch 205, the trunk 202, 203 and 204 may be again seized in the above-described manner.

5 Establishment of a connection to a magneto exchange.

It will now be assumed that the calling subscriber desires to establish a connection with a subscriber whose substation is No. 450 located in an outlying exchange which is of the magneto type. Upon the initiation of the call, the operator extends a connection through the plug 101 to the calling subscriber's line in the manner previously described, and the fundamental circuit extending through the relay 113 in position 3 of sequence switch 105, and through the stepping relay 315 in position 4 of sequence switch 301 is established in the manner previously described. The operator, in response to the instructions of the calling subscriber, depresses the key 340 in the first row of digit keys and the start key 312. Whenever key 340 is depressed the selector switch 112 is controlled to direct the connection directly to a magneto office and since no final selector is employed on such connections, the key is provided with an additional contact for advancing the sender sequence switch to position 16, thus preventing the sender from exercising further control over the connection. The group selector is now driven in the manner previously described under the control of the counting relays to position its brushes in association with the fourth group of trunks terminating in its bank 129.

When the switch shaft has been so positioned, the upper counting relay O energizes, opening at its outer left-hand armature and back contact the fundamental circuit extending through the relay 113 and the stepping relay 315, and at its inner left-hand armature and front contact closes a circuit extending through sequence switch contact 324 for driving sequence switch 301 out of position 4. Upon leaving position 4, the locking circuit for the bank of counting relays is opened at sequence switch contact 320 but, since the operator has depressed key 340 corresponding to the group of trunks extending to the desired magneto exchange, a new circuit is established for the lower counting relay O as soon as sequence switch 301 reaches position 5, this circuit extending from grounded battery, through the winding of the lower counting relay O, through the conductor 341, sequence switch contact 342, and thence to ground at the right-hand contacts of key 340. This circuit is maintained at sequence switch contact 342 through position 5½. When the lower counting relay O energizes, a locking circuit is closed through the winding of the lower counting relay O

which may be traced from grounded battery, through the winding of this relay, through the winding of the upper counting relay O, and thence to ground at sequence switch contact 320. The upper counting relay O energizes in this locking circuit as soon as the shunt around its winding is removed at sequence switch contact 342, when the sequence switch leaves position 54. The energization of the upper counting relay O closes a circuit at its inner armature and front contact for driving sequence switch 301 out of position 6 and into position 16. 70 75

Following the operation of the selector switch in accordance with the first digit of the number when relay 113 became energized, sequence switch 105 was driven out of position 3 and into position 6 as previously described, and the selector switch is thereupon caused to hunt for an idle trunk circuit in the group to which its brushes have selectively moved, and upon the selection of an idle trunk circuit, the sequence switch 105 is driven into position 11 in the manner previously described. Since now the sequence switch 301 is in position 16, a circuit is established from ground at sequence switch contact 335, extending over conductor 336 and through sequence switch contact 155, for driving the sequence switch 105 out of position 11 and into position 16

A circuit is now established over the selected trunk conductors 250 and 251 for the trunk relay 400 associated with the incoming end of the selected interoffice trunk. The circuit for this relay extends from grounded battery, through its right-hand winding, the back contact and upper armature of cut-off relay 401, over trunk conductor 250, selector brush 124, sequence switch contact 170, through the winding of polarized supervisory relay 161, sequence switch contact 171, selector brush 125, trunk conductor 251, intermediate armature and back contact of relay 401, and thence to ground through the left-hand winding of relay 400. Relay 400 energizes in this circuit and, at its left-hand armature and front contact, closes a circuit through the winding of slow releasing relay 402, and also a circuit in parallel with the winding of relay 402, extending through the lower winding of ringing relay 403. Relay 402, upon energizing, closes at its right-hand armature and front contact, a circuit extending through the upper winding of relay 403, and at its left-hand armature and front contact, closes a circuit extending from ground at the right-hand armature and front contact of relay 400, through the left-hand armature and front contact of relay 402, and thence to grounded battery, through the winding of the trunk holding relay 404. Relay 404 energizes in this circuit and at its upper armature 130

ture and front contact, closes a locking circuit for itself extending over the test conductor 252 of the interoffice trunk circuit, through the brush 126 of the group selector, 5 conductor 152, inner left-hand armature and back contact of test relay 138, and thence to ground.

Ringing relay 403, upon energizing, connects the source of ringing current 405 to 10 the incoming end of the trunk circuit for operating the drop signal 406, this circuit extending from a source of ringing current 405, through the front contact and intermediate armature of relay 403, through the 15 ring jack contact 407, the winding of drop signal 406, the tip jack contact 408, and thence to ground at the upper armature and front contact of ringing relay 403. Current from the source of ringing current 405 20 causes the operation of the drop signal to signal the operator at the magneto exchange office that a call is incoming over the inter-office trunk with which the drop signal is associated.

25 At the time relay 404 energized, a circuit was closed for relay 401 extending from grounded battery, through the winding of this relay, through the lower armature and front contact of relay 404, and thence to 30 ground at the front contact and lowermost armature of ringing relay 403. Relay 401, upon energizing, opens at its upper and intermediate armatures and back contacts, the circuit extending through the windings of 35 trunk relay 400, and at these armatures and their front contacts, extends the talking conductors of the trunk circuit to the back contacts of the upper and intermediate armatures of ringing relay 403. Relay 400, upon 40 becoming disconnected from the interoffice trunk circuit, immediately deenergizes, opening the initial energizing circuit extending through the lower winding of ringing relay 403 and the circuit extending in 45 parallel therewith, through the slow release relay 402. The slow release relay 402 deenergizes after an interval, opening at its right-hand armature and front contact, the circuit extending through the upper winding 50 of relay 403, and the ringing relay 403 thereupon deenergizes to disconnect the source of ringing current 405 from the winding of the drop signal 406. At its lowermost armature and front contact, relay 401 55 closes a locking circuit for itself which extends to ground at the right-hand armature and back contact of relay 402 as soon as relay 402 deenergizes. A second locking circuit is also closed for relay 401 through the 60 back contact and lowermost armature of ringing relay 403.

The operator at the magneto exchange, upon noting the operation of the drop signal 65 406, selects an idle cord circuit at her position and inserts the answering plug 409

thereof in the jack of the trunk circuit which has been seized for the use of the calling subscriber at the automatic exchange, thereby cutting off the drop signal 406 at the jack springs, and depresses her listening 70 key 410 to connect her telephone set 411 to the cord circuit. The operator then receives instructions from the calling subscriber as to the number of the line desired in the magneto exchange and, in accordance with 75 such instructions, inserts the calling plug 412 of the cord circuit in the jack 413 of the desired line. She then proceeds to call the subscriber on the desired line by applying ringing current from the source 414, 80 through the contacts of ringing key 415. Upon the response of the called subscriber, the subscribers are connected into a talking circuit extending over the heavy conductors. The calling subscriber receives talking current 85 from the battery in the cord circuit at the automatic exchange and the called subscriber is provided with talking current from a source local to his substation.

Upon the termination of the conversation, 90 the calling subscriber restores his receiver to its switchhook, thereby opening the circuit extending through the supervisory relay 160 which upon deenergization causes the operation of the usual supervisory signal. 95 The operator, in response to this signal, removes the plug 101 from the jack 102, causing thereby the deenergization of relay 103 which, at its armature and back contact, closes a circuit for driving sequence switch 100 105 into position 18. In position 18, the selector switch is restored to normal position in the manner previously described and, upon reaching normal position, closes a circuit for driving sequence switch 105 out of 105 position 18 and into position 1.

Upon the restoration of the switch shaft of selector 112 and the removal of the switch brushes from the terminals of the interoffice trunk, the holding circuit of relay 404 is 110 opened and this relay thereupon becomes deenergized, closing at its lower armature and back contact, a circuit for the ringing relay 403 which extends from grounded battery, through the lower winding of this relay, 115 through the left-hand armature and back contact of trunk relay 400, the back contact and lower armature of relay 404, the lowermost armature and front contact of relay 401, and thence to ground at the back contact 120 and lowermost armature of relay 403. Relay 402 is also energized in parallel with the lowermost winding of relay 403, closing at its right-hand armature and front contact, a circuit extending through the upper winding 125 of relay 403. Relay 403, upon energizing, again connects the source of ringing current 405 to the incoming ends of the interoffice trunk circuit and since now the plug 409 130 is in the jack of the trunk circuit, the ring-

ing current is connected to the winding of the clearing-out drop signal 416 associated with the operator's cord circuit. The energization of relays 402 and 403 has opened the locking circuit of relay 401 which now de-energizes, opening at its lowermost armature and front contact, the initial energizing circuit for relays 402 and 403, which relays, after an interval, deenergize, the relay 403 thereby disconnecting the source of ringing current 405 from the trunk circuit.

The operator at the magneto exchange, upon noting the operation of the clearing-out signal 416 pulls down the cord circuit from the jack of the interoffice trunk and from the jack of the called line. The circuits which were employed in extending a connection from the calling subscriber's line 100 in the automatic exchange to the called subscriber's line 450 in the magneto exchange are now completely restored to normal condition.

It is apparent from the foregoing description that the seizure of an interoffice trunk by a group selector in the automatic exchange automatically effects the application of a source of ringing current to the incoming end of the interoffice trunk for operating a drop signal, and without the employment of any source of current at the group selector of the automatic exchange. The circuits associated with the incoming end of the interoffice trunk are also effective for connecting the source of ringing current to the cord circuit at the magneto exchange for automatically producing a disconnect signal upon the release of the interoffice trunk circuit at the outgoing end thereof. It is further apparent that the relation of the winding of the slow relay 402 and the armature contacts of such relay, with the windings of the double wound ringing relay 403, is such that upon a momentary impulse of current through one winding of relay 403, the relay 403 is caused to maintain its energization for an appreciable period after the cessation of such impulse of current. This feature is particularly important in that it enables the source of ringing current to be connected to the winding of the drop signals 406 and 416 for a sufficient period to insure the operation of the signals.

What is claimed is:

1. In a telephone exchange system, an originating office, an outlying office, trunk lines extending between said offices, an automatic switch in said first office for selecting one of said trunk lines, responsive means individual to said trunk line at the outgoing end thereof, a signal associated with said trunk line at the incoming end thereof, means made effective by the seizure of said trunk line by said switch to operate said responsive means, and means under the control of said responsive means for operating said signal.

2. In a telephone exchange system, an originating office, an outlying office, trunk lines extending between said offices, a cord circuit at said second office for connection with said trunk lines, an automatic switch in said first office for selecting one of said trunk lines, responsive means associated with said trunk at the outgoing end thereof, a signal associated with said trunk line at the incoming end thereof, a second signal in said cord circuit, and means made effective by the seizure of said trunk line by said switch to operate said responsive means to thereby operate said first signal and effective upon release of said trunk line to operate said second signal.

3. In a telephone exchange system, an originating office, an outlying office, trunk lines extending between said offices, a cord circuit at said second office for connection with said trunk lines, an automatic switch in said first office for selecting one of said trunk lines, a drop signal in said cord circuit, and means made effective by release of said trunk line at the outgoing end thereof to operate said signal.

4. In a telephone exchange system, an originating office, an outlying office, trunk lines extending between said offices, a group selector and a final selector in said first office for extending connections within said first office, said group selector also being adapted to extend a connection to one of said trunk lines, a drop signal associated with said trunk line at the incoming end thereof, and means made effective by seizure of said trunk line by said group selector to operate said signal.

5. In a telephone exchange system, an originating office, an outlying office, trunk lines extending between said offices, a group selector and a final selector in said first office for extending connections within said first office, said group selector also being adapted to extend a connection to one of said trunk lines, a cord circuit at said second office for connection with said trunk lines, a drop signal associated with said trunk line at the incoming end thereof, a second drop signal in said cord circuit, and means made effective by seizure of said trunk line by said group selector to operate said first signal and effective upon release of said trunk line to operate said second signal.

6. In a telephone exchange system, an originating office, an outlying office, trunk lines extending between said offices, an automatic switch in said first office for selecting one of said trunk lines, a drop signal associated with said trunk line at the incoming end thereof, a source of alternating current for operating said signal, and means made effective by the seizure of said trunk line by said switch to connect said source in circuit with said signal.

7. In a telephone exchange system, an originating office, an outlying office, trunk lines extending between said offices, an automatic switch in said first office for selecting 5 one of said trunk lines, a drop signal associated with said trunk line at the incoming end thereof, a source of alternating current for operating said signal, a trunk relay normally connected across said trunk circuit, 10 a double wound signaling relay for connecting said source of current with said signal, a slow releasing relay, means under the control of said trunk relay for energizing said slow relay and one winding of said 15 signaling relay in parallel, and means under the control of said slow relay for closing a maintaining circuit for said signaling relay through the second winding of said latter relay.
- 20 8. In a telephone exchange system, the combination of a group of relays comprising a double wound relay and a slow releasing relay, one winding of said first relay being connected in parallel with the winding of 25 said second relay and the other winding of said first relay being connected into a circuit under the control of said second relay, whereby said first relay may be maintained energized for an appreciable interval after the cessation of the initial impulse of energizing current through the first-mentioned winding thereof.
- 30 9. In a telephone exchange system, a trunk line, a signaling device associated with said trunk line, a source of current for operating 35 said device, a relay mechanism for connecting said source of current to said device comprising a double wound relay and a slow releasing relay, one winding of said first relay being connected in parallel with the 40 winding of said second relay, and the other winding of said first relay being connected into a circuit under the control of said second relay, whereby said first relay may be maintained energized for an appreciable interval after the cessation of the initial impulse of energizing current through the first-mentioned winding thereof.
- 45

In witness whereof, I hereunto subscribe my name this 24 day of April, A. D. 1920.

ALBEN E. LUNDELL
